(57) **CLAIM**

The ornamental design for a plumbing fitting, as shown and described.

DESCRIPTION

In a preferred embodiment, the nature of this product is as a plumbing fitting in the form of a showerhead, or a support arm therefore, primary useful for washing body parts.

FIG. 1 is a left, top, front perspective view of a plumbing fitting of my new design;

FIG. 2 is a left side elevational view thereof, the right side elevational view thereof being a mirror image of the left side shown;

FIG. 3 is a top plan view thereof;

FIG. 4 is a front elevational view thereof; and,

FIG. 5 is a bottom plan view thereof.

The broken line representations of support arm environment in FIGS. 1–5, and nozzle face structure in FIGS. 1, 4 and 5 are for the purpose of illustration only, and form no part of the claimed design.
